(57) **CLAIM**

The ornamental design for a power adapter for electric vehicle charging, as shown and described.

DESCRIPTION

FIG. 1 is a front left perspective view of a power adapter for electric vehicle charging showing our new design;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof; and,

FIG. 7 is a bottom plan view thereof.

The broken lines shown in the drawings illustrate portions of the power adapter for electric vehicle charging that form no part of the claimed design.
